(57) **CLAIM**

I claim the ornamental design for a V-shaped pull, as shown and described.

DESCRIPTION

FIG. 1 is a front elevational view of a V-shaped pull design; FIG. 2 is a rear elevational view thereof; FIG. 3 is a right side elevational view thereof; FIG. 4 is a left side elevational view thereof; FIG. 5 is a top plan view thereof; FIG. 6 is a bottom plan view thereof; and, FIG. 7 is an environmental perspective view thereof, shown in a position of use. The broken lines shown represent unclaimed subject matter and form no part of the claimed design.
